US00D785483S

(12) **United States Design Patent** (10) **Patent No.:** **US D785,483 S**
(45) **Date of Patent:** **** May 2, 2017**

(54) **ARTICLE OF JEWELRY**

(71) Applicant: **Alex and Ani, LLC**, Cranston, RI (US)

(72) Inventor: **Carolyn A. Rafaelian**, Cranston, RI (US)

(73) Assignee: **Alex and Ani, LLC**, Cranston, RI (US)

(**) Term: **14 Years**

(21) Appl. No.: **29/521,776**

(22) Filed: **Mar. 26, 2015**

(51) LOC (10) Cl. **11-01**

(52) U.S. Cl.

USPC **D11/5**

(57) **CLAIM**

The ornamental design for an article of jewelry, as shown and described.

DESCRIPTION

FIG. 1 is a perspective view of an article of jewelry showing my new design;

FIG. 2 is a front plan view of the article of jewelry of FIG. 1;

FIG. 3 is a rear plan view of the article of jewelry of FIG. 1;

FIG. 4 is a left side view of the article of jewelry of FIG. 1;

FIG. 5 is a right side view of the article of jewelry of FIG. 1;

FIG. 6 is a top view of the article of jewelry of FIG. 1; and,

FIG. 7 is a bottom view of the article of jewelry of FIG. 1. The term "INDICIA" shown in broken lines forms no part of the claimed design.

1 Claim, 5 Drawing Sheets
